DESIGN FOR A PLATE OR SIMILAR ARTICLE

Earl W. Newton, Chicago, Ill., assignor to Imperial Glass Corporation, Bellaire, Ohio, a corporation of Ohio

Application May 19, 1936, Serial No. 62,724

Term of patent 7 years

To all whom it may concern:

Be it known that I, Earl W. Newton, a citizen of the United States of America and resident of Chicago, county of Cook, and State of Illinois, have invented a new, original, and ornamental Design for a Plate or Similar Article, of which the following is a specification, reference being had to the accompanying drawing, in which—

Figure 1 is a top plan view of a plate or similar article, showing my new design;

Figure 2 is a side elevational view of the same; and

Figure 3 is a vertical sectional view taken on line 3—3 of Fig. 1.

I claim:

The ornamental design for a plate or similar article, substantially as shown.

EARL W. NEWTON.
